DESIGN FOR A LACE

Joseph A. Sutton, New York, N. Y.

Application April 29, 1941, Serial No. 100,690

Term of patent 3½ years

To all whom it may concern:

Be it known, that I, Joseph A. Sutton, a citizen of the United States of America, residing in New York city, county of New York and State of New York, have invented a new, original, and ornamental Design for a Lace, of which the following is a specification, reference being had to the accompanying drawing, forming part thereof, wherein,

The figure of the drawing is a plan view of a lace showing my new design.

I claim:

The ornamental design for a lace, as shown.
JOSEPH A. SUTTON.
